(57) **CLAIM**

The ornamental design for a wrap dock, as shown and described.

DESCRIPTION

FIG. 1 is a perspective view of the wrap dock;

FIG. 2 is a first side view of the wrap dock;

FIG. 3 is a second side view of the wrap dock;

FIG. 4 is a front view of the wrap dock;

FIG. 5 is a back view of the wrap dock;

FIG. 6 is a top view of the wrap dock;

FIG. 7 is a bottom view of the wrap dock; and,

FIG. 8 is a perspective view of an open wrap dock. The broken lines shown in the figures represent portions of the wrap dock that form no part of the claimed design.
